UNITED STATES PATENT OFFICE

2,167,341

KEY DUPLICATOR

David B. Willock, Kansas City, Mo.

Application April 1, 1937, Serial No. 134,241

6 Claims. (Cl. 29—76)

My invention relates to improvements in key duplicators.

It relates particularly to an apparatus adapted for duplicating keys the blades or bits of which have notched edges, such as keys for cylinder locks.

It is adapted for use in connection with a manually operated cutting implement, such as a file.

One of the objects of my invention is the provision in an apparatus of the kind described of novel means for guiding and limiting the cutting action of the cutting implement.

Another object of my invention is the provision of a novel carriage for supporting the implement guiding and limiting means and the guide which cooperates with the pattern from which the blank key is copied.

Still another object of my invention is the provision of novel means for properly positioning the blank to be cut with reference to the pattern.

A further object of my invention is the provision of a key duplicator of the kind described which is simple, cheap, strong, durable, not likely to get out of order, which is efficient in its operation, and with which an unskilled person can easily and quickly duplicate a key.

The novel features of my invention are herein-after fully described and claimed.

In the accompanying drawing, which illustrates the preferred form of my invention,

Fig. 1 is a plan view of my improved key duplicator.

Fig. 2 is a front view, partly in elevation and partly in vertical section.

Fig. 3 is an end elevation, partly broken away, of the apparatus.

Fig. 4 is a front view, partly broken away, showing the carriage moved from the position in which it is shown in Fig. 2.

Fig. 5 is a perspective view of the pattern guide.

Fig. 6 is a perspective view of the pattern clamping member.

Similar characters of reference designate similar parts in the different views.

The duplicator is provided with a support comprising a rectangular base 1 from the rear corners of which respectively upwardly extend two posts 2 between which and supported by them is a horizontal bar 3 on which is slidably and pivotally mounted the rear portion of a carriage

4.

Means for clamping a pattern key 5, of a common "Yale" type having in one edge of its blade 6 serrations or notches 7, consists of a rectangular plate 8 having in its upper edge and rear

side a longitudinal groove 9 adapted to receive therein and hold edge up the blade 6 of the pattern. Two screws 10 extending through the plate 8 and respectively fitted in threaded holes in the front edge of the base 1, hold the plate 8 clamped to the pattern and the latter clamped to the base 1, with the serrated upper edge of the blade 6 parallel with the carriage supporting bar 3.

A pattern guide comprising a rod 11, square in cross section, is fastened rigidly to the under side of the carriage 4 by a plate 12 secured to the carriage by a screw 13, Fig. 3. The guide 11 is disposed so as to extend over the blade 6 on the upper edge of which it is adapted to rest with its lower longitudinal corner portion disposed in the notch 7 that is to be cut at the time correspondingly in the blade of the key blank.

The key blank 14 is mounted in a groove 15 in the upper edge and rear side of a plate 16, which is fastened by two screws 17, directly above the plate 8, to the front side of a bar 18, which is parallel with the bar 3, and which is disposed and is vertically longitudinally adjustable in two recesses 19 provided respectively in the front sides of two front corner posts 20 on the base 1.

For adjusting the bar 18 lengthwise it has bearing respectively against its ends two screws 21 respectively fitted in threaded holes in the posts 20. For raising respectively the ends of the bar 18, it has fitted in vertical threaded holes extending through it, two screws 22, the lower ends of which bear on the posts 20 respectively. The screws 22 respectively extend upwardly through two slots 23 in the upper ends of the posts 20 above the recesses 19. These slots permit the screws 22 to be moved with the bar 18 when it is adjusted lengthwise.

For limiting the upward movement of the bar 18, it has bearing on its upper edge the lower ends of two screws 24 respectively fitted in vertical threaded holes extending through the upper ends of the posts 20 to the recesses 19 respectively.

Two screws 25 respectively extend through two holes 26, larger in diameter than the shanks of the screws 25, and are respectively fitted in two horizontal holes provided in the posts 20.

For guiding and limiting the cutting movement of a linearly reciprocative cutting implement, such as a file 27, shown in dotted lines in Fig. 2 and in solid lines in cross section in Fig. 4, means are provided which preferably comprise two guiding rollers 28 which are respectively rotatably mounted on the carriage 4 at the front and

rear of the bar 18 and of the blade of the blank 14.

Each of the rollers 28 is rotatable on an axis parallel with the bar 3, and each is provided 5 with an annular right angled peripheral groove which aligns with the groove of the other roller transversely to the blade of the blank 14. The file 27 is of a form adapting it to fit in the grooves, designated by 29, in the rollers 28. The 10 bottoms of the grooves 29 are in a vertical plane which longitudinally bisects the pattern guide 11.

The file 27, when disposed in the grooves 29 of the rollers 28, is guided by the latter, so as to be disposed in the same vertical plane as the pattern 15 guide 11, so that when the pattern guide 11 is disposed in a groove 7 of the pattern key 5, the file 27, when operated, will cut a corresponding groove in the upper edge of the blade of the blank 14. The clamping plates 8 and 16 are disposed so that the blank 14 is held above and 20 coincides in position with the pattern key 5.

The grooves in the blank 14 are consecutively cut to correspond with the notches or serrations 7 in the pattern key blade 6, the bottoms of the 25 grooves 29 of the rollers 28 limiting the downward cutting of the file 27 into the blade of the blank 14.

As the grooves or notches are cut consecutively in the blade of the blank 14, the carriage 4 is moved along on the rod or bar 3, so that the pattern 30 guide 11 can consecutively enter the notches 7 of the pattern key blade 6. As the carriage 4 is hinged on a horizontal axis on the bar 3, it can be swung upwardly and downwardly to 35 change the pattern guide 11 from notch to notch in the pattern blade 6.

In operation, the pattern key 5 is clamped by the plate 8, with the notched edge of the blade 6 up, against the base 1. The blank 14 is then 40 clamped edge up, as shown, by the plate 16 against the bar 18. The screws 21, 22 and 24 are then adjusted so as to properly position the blank 14 with respect to the pattern key 5 after which the screws 25 are tightened so as to hold 45 the bar 18 in the adjusted position.

The carriage 4 is then moved to position the pattern guide 11 in one of the notches 7 of the blade 6 of the pattern key. The operator then 50 disposes the file 27 with one longitudinal edge resting on the upper edge of the blade of the blank 14 in the grooves 29 of the rollers and files a notch in the blank, the rollers 28 guiding the 55 file and limiting its downward movement to make the notch cut thereby correspond in depth and shape to the notch in the pattern key containing the pattern guide 11.

By having the blank supporting member 18 adjustable lengthwise and vertically and laterally at each end it is adapted for holding and properly 60 positioning a key blank 14, that is quite dissimilar in form from the pattern key 5. This is very advantageous because keys of different manufacturers vary considerably in form for a like type of key, and the person duplicating the key may 65 not have at hand a blank corresponding to the key to be duplicated. With the adjustment provided for the blank supporting member 18, the operator can quickly mount the blank and have it held firmly in correspondence with the key 5.

70 By having the key blank supporting means disposed above and parallel with the blade of the pattern, looseness between the carriage 4 and the bar 3 on which it slides and turns, which enables the carriage to twist laterally, has a minimum of detrimental effect. As the guide 11 sup-

ports the carriage on the pattern key 5, and the middles of the file guiding rollers 28 are in the vertical plane of the guide 11, any lateral movement of the file guiding rollers due to looseness will substantially parallel with the upper edge 5 of the blank 14, and will not increase the depth of the file cut to any appreciable degree, and the file will cut a proper duplicate of the pattern key.

What I claim is:

1. In a key duplicator, a base, means thereon 10 for holding a pattern and a key blank one above the other with their blades parallel, and disposed horizontally, a carriage horizontally reciprocative on said base and hinged thereto on a horizontal axis, a guide on said carriage disposed so as to be 15 adapted to rest on the blade of said pattern, and means on said carriage for supporting and guiding a linearly reciprocative cutting instrument across and for limiting its downward movement into the blade of said blank.

2. In a key duplicator, a base, means thereon 20 for holding a pattern and a key blank one above the other with their blades parallel and disposed edge up horizontally, a carriage horizontally reciprocative on said base and hinged thereto on a 25 horizontal axis, a guide on said carriage disposed so as to be adapted to rest on the upper edge of the blade of said pattern, and two peripherally grooved guiding rollers rotatable on said carriage at opposite sides respectively of the blade of said 30 blank and having their grooves transversely aligned to said blade of said blank and adapted to receive and to guide a cutting instrument across the upper edge of the blade of said blank and limit the downward movement of said instrument 35 into the blade of said blank.

3. In a key duplicator, a base, means thereon 40 for holding a pattern having a blade with a serrated edge disposed edge up, means on said base for holding a key blank with its blade disposed above and parallel with the blade of said pattern and having its edge to be cut facing upwardly, a carriage reciprocative on said base parallel with the blade of said pattern and hinged to said base so as to swing transversely to its direction of 45 movement on said base, a guide on said carriage disposed so as to be adapted to rest on said serrated edge, and means on said carriage for guiding a linearly reciprocative cutting instrument across and for supporting and limiting its movement 50 into the upper edge of the blade of said blank.

4. In a key duplicator, a base, means thereon 55 for holding a pattern having a blade with a serrated edge disposed horizontally edge up, means on said base for holding a key blank with its blade disposed edge up above and parallel with the blade of said pattern, a carriage reciprocative on said base parallel with the blade of said pattern and hinged to said base so as to swing transversely to its line of movement on said base, a guide on said carriage disposed so as to rest on said serrated edge, and means on said carriage at opposite sides of said blank holding means for guiding a cutting implement across and for limiting its downward movement into the upper edge 60 of the blade of said blank.

5. In a key duplicator, a base, means thereon 65 for holding the blade of a pattern with its serrated edge up, a member on said base parallel with said blade adjustable horizontally lengthwise and vertically at each end and having means for holding a key blank above and with its upper edge parallel with said blade, a carriage reciprocative on said base parallel with said blade and 70

hinged to said base so as to swing transversely to said blade, a guide on said carriage disposed so as to be adapted to rest on said serrated edge, and two peripherally grooved guiding rollers rotatably mounted on said carriage at opposite sides respectively of said key blank holding means and having their grooves aligned and adapted to receive and guide a cutting implement transversely across and limit its movement downwardly into the upper edge of said blank.

6. In a key duplicator, a base, means for supporting edge up thereon a pattern, a carriage reciprocal on said base and hinged thereto to

swing transversely to said pattern, a pattern guide carried by said carriage and disposed so as to be adapted to rest on said pattern, a member adjustable lengthwise and adjustable at each end vertically and horizontally on said base for supporting a blank to be cut in proper relation to said pattern, and means for guiding a cutting implement transversely across and in contact with said blade and for limiting its cutting movement downwardly into said blank in conformity with the disposition of said pattern guide on said pattern. 5
